DUAL CYLINDER VEHICLE LIFT

Gilbert W. Gaarder and Edwin L. Vollmer, St. Joseph, Mo., assignors to Gray Manufacturing Company, Inc., St. Joseph, Mo., a corporation of Missouri

Filed Mar. 3, 1969, Ser. No. 16,002

Term of patent 14 years

Int. Cl. D12—05

U.S. Cl. D41—1

FIG. 1 is a top plan view of the dual cylinder vehicle lift;

FIG. 2 is a side elevational view of one side thereof;

FIG. 3 is a fragmentary side elevational view showing the side opposite to that shown in FIG. 2;

FIG. 4 is a fragmentary elevational view of the front end thereof; and

FIG. 5 is a fragmentary elevational view of the rear end of the dual cylinder vehicle lift.

We claim:

The ornamental design for a dual cylinder vehicle lift, as shown.
